WINDOW FASTENER

Filed May 27, 1929

UNITED STATES PATENT OFFICE

CHARLES S. BUTTERFIELD, OF MARTINEZ, CALIFORNIA

WINDOW FASTENER

Application filed May 27, 1929. Serial No. 366,434.

My invention relates to improvements in window fasteners, and it consists in the combinations, constructions and arrangements hereinafter described and claimed.

5 An object of my invention is to provide a window fastener that is designed to take the place of putty. The fastener consists of two pieces with a layer of soft material disposed between one of the pieces and the window pane. One of the pieces is first secured in place and then the other piece is secured to the first one.

10 A further object of my invention is to provide a device of the type described which is simple in construction and which is durable and efficient for the purpose intended.

15 Other objects and advantages will appear in the following specification, and the novel features of the device will be particularly 20 pointed out in the appended claims.

My invention is illustrated in the accompanying drawing forming a part of this application, in which

25 Figure 1 is a front elevation of a window showing the device applied in place;

Figure 2 is a section along the line 2—2 of Figure 1;

Figure 3 is a top plan view of Figure 4;

30 Figure 4 is a front elevation of one of the pieces;

Figure 5 is a plan view of the other piece; and

Figure 6 is an enlarged sectional view of the device.

35 In carrying out my invention, I make use of a window sash 1 that has a molding 2 formed therein for receiving a window pane 3. The pane is held against the molding 2 by means of my device which will now be described.

40 As already stated, the device consists of two parts. Reference to Figure 6 shows that one of the parts 4 is angular in shape and is provided with a base portion 5 and a vertically-extending portion 6.

45 Figure 2 shows the base portion 5 as resting upon a ledge 7 formed in the window sash 1. The front of the base 5 is bent downwardly and then upwardly for forming a flange 8 that bears against the side of the

window sash. The part of the metal forming the flange is inclined upwardly and inwardly, as at 9, for forming a retaining flange.

55 The portion 6 has tongues 10, these normally extending in the same plane as the portion 6, as shown in Figure 4. The base is secured to the window sash by nails 11, (see Figure 2), that are driven through openings 12, (see Figure 6).

60 Between the portion 6 and the window pane 3, I dispose a felt strip 13 or other suitable soft material.

65 The pieces 4 are disposed around the marginal edges of the window pane and then the pieces 14 are secured in place. The edges 15 of the pieces 14 are disposed in back of the retaining flanges 9 and then the pieces 14 are rocked down into place so as to have their upper edges 16 bear against the portions 6. The tongues 10 are now crimped so as to enter recesses 17, (see Figure 5), and to engage with the pieces 14 in the manner shown in Figure 1. This completes the assembly of the device.

70 The device can be secured to a window sash quickly and will make a neat and trim appearance after being disposed in place.

75 Although I have shown and described one embodiment of my invention, it is to be understood that the same is susceptible of various changes, and I reserve the right to employ such changes as may come within the scope of the appended claims.

I claim:

1. A window fastener comprising a frame triangular in shape in cross section, said frame comprising two pieces and cooperating means carried by the pieces for securing them together.

2. A window fastener comprising a strip angular in cross section, means for securing the strip to a window sash, a piece for covering the securing means and cooperating means carried by the strip and piece for securing them together.

3. The combination with a window sash having a window opening therein, a window pane disposed in the opening, of strips disposed about the marginal edges of the win-

100

dow pane, said strips being angular in cross section, means for securing the strips to said window sash, each strip having a flange bearing against the outer surface of the sash, said flanges having inwardly inclined portions and pieces disposed against the inwardly-inclined portions and being secured to said strips.

4. A window fastener comprising a strip angular in cross section, said strip having 10 openings in its base portion for receiving fastening means, the front of the base being bent into a flange for bearing against the surface of a window sash and being further bent into an inwardly-extending portion and 15 a piece secured to said strip, said piece bearing against the inclined portion and cooperating means carried by the strip and piece for securing the piece to the strip.

5. A window fastener comprising a strip 20 angular in cross section, said strip having openings in its base portion for receiving fastening means, the front of the base being bent downwardly and then upwardly for forming a depending flange for bearing against the front surface of a window sash, the upwardly bent portion being inclined inwardly for forming a groove with the base portion, and a cover piece having its lower 25 edge placed in the groove and its upper edge resting against the top of the upwardly extending portion of the angular strip, and projections carried by the strip and being bendable into recesses in the piece for securing the piece in position.

35 CHARLES S. BUTTERFIELD.
